SPARKING YO-YO

Michael J. De Vincent and Thomas C. Pomatico,
Brooklyn, N. Y.

Application July 12, 1949, Serial No. 104,241

9 Claims. (Cl. 46—48)

1

This invention relates to toys, and more particularly to a sparking yo-yo.

A particular feature of novelty and advantage of the present invention, in contradistinction to the sparking yo-yos of the prior art, is the provision of a yo-yo having its sparking members wholly contained within the yo-yo, whereby when the yo-yo is reciprocated away from and toward the operator, a brilliant shower of sparks is emitted, yet the sparks are not discharged externally of the device, and it is thus possible for it to be operated with perfect safety by children.

Other features of novelty and advantage of the improved safety yo-yo of the present invention include the provision of a hollow body, desirably of apposed, spaced cups, mounted on an axis, the driving member or pulley being centered on the axis with the cord secured to the pulley, or looped therearound, and a yoke member loosely mounted on the axis and held in relatively fixed position by the cord passing therethrough, the hollow, bipartite body, having apertures protected by transparent window material, serving as the momentum member. An additional feature of novelty and advantage of the invention herein is the provision of mounting the coating sparking members, that is, the flints and cooperating abrasive surfacing, on the yoke and the surfaces of the inside of the hollow cups, or the outer surfaces of the yoke, or vice-versa, the flints being mounted singly or in multiple.

The above and other desirable features of novelty and advantage of the present invention will be more clearly appreciated and understood by reference to the following description, including the drawings, and to the appended claims.

In the drawings, like numerals refer to similar parts throughout the several views, of which

Fig. 1 is a side elevation of an improved yo-yo showing the viewing apertures;

Fig. 2 is a view similar to Fig. 1, with one-half of the casing removed, and showing the mounting of one form of yoke with contained flints and driving cord;

Fig. 3 is a vertical section taken on line 3—3 of Fig. 1, with the pulley and axis being shown in elevation;

Fig. 4 is an elevation of the inside of a casing member shown in Figs. 1 to 3, and illustrating one method of mounting the abrasive surfacings;

Figs. 5 and 6 are views respectively similar to Figs. 2 and 3, and showing a modified form of yoke with attached flints;

Fig. 7 is an elevation of the yoke shown in Figs. 2 and 3;

2

Fig. 8 is an elevation of the yoke shown in Figs. 5 and 6;

Fig. 9 is a view similar to Fig. 3, showing the abrading surfacings on the outer faces of the pulley and the flint-carrying yoke biased to effect bearing engagement of the flints against the abrading surfacings;

Fig. 10 is a view taken on line 10—10 of Fig. 9, with one-half the casing removed and the yoke shown in elevation;

Fig. 11 is a vertical transverse section of a modified form of the yo-yo of Fig. 9, showing the flints mounted in the casing members;

Fig. 12 is an elevation, partly in broken section, of the device of Fig. 11;

Fig. 13 is an elevation of the yoke member of Figs. 9 to 12, and

Fig. 14 is a view similar to Figs. 3, 6, 9 and 11, showing a cord looped around the axis and twisted on itself.

Referring to Figs. 1—10 of the drawings, the novel toy herein is seen to comprise a body 10, formed of identical cup shaped halves or sections 11, demountably secured to axis 12, as by machine screws 13. The sections 11, as shown, are dished, and the rims 14 are curved inwardly to define curvilinear surfaces 15. The rounded rims 15 of cooperating sections 11, mounted on the axis 12, are spaced to define a circumferential slot 16. The slot 16 is in the plane of the perpendicular bisector of axis 12, and is wide enough to permit a top cord to pass freely, and without binding, between curvilinear bearing surfaces 15. The dished halves 11 of the device may be flattened, as indicated at 17, and are provided with openings 18, serving as windows. The windows 18 are desirably covered with colored, translucent plastic sheets, or the like, to give a varicolored effect to the spark display.

As shown in Figs. 1 to 6, 9 and 10, a pulley 20 is formed by spaced disks 21, 22, which are fixedly mounted on the axis and define a central spindle section 23, on the axis. The spacing between the disks corresponds to the width of the peripheral slot 16, with the spindle section 23 in the plane of the slot 16. The width of aligned slot 16 and spindle 23 is slightly greater than that of cord 24, which may be threaded through a hole in the spindle section and secured by a knot 25. This construction insures that the cord will be wound up as a flat spiral lying in the dead center of the device, thereby precluding the yo-yo from wobbling during its spinning operation.

The sparking mechanism of the improved yo-yo, 55 in a preferred form, as shown in Figs. 1—6, com-

prises an abrasive surface 30 mounted on the inner surface of each of the cup or shell sections 11, and sparking elements or flints, designated generally by the numeral 40. As shown in Figs. 9-12, abrasive surfaces 31, are provided on the outer surfaces of the spaced disks 21, 22. The cooperating flints are mounted in yoke members, as will now be described:

In the yo-yo illustrated in Figs. 1-4, and 7, the flint-carrying yoke 32 comprises a pair of symmetrical disk sections 33, joined by a bridging section 34, having a centered aperture 35, aligned with and of the same diameter as the width of peripheral slot 16 and spindle 23. The disk sections 33 are provided with aligned central apertures 36, which are larger than and ride freely over the axis 12, on both sides of the pulley 20. As shown, these disk sections are also provided with a plurality of marginal apertures 37, which serve to mount the flints 40. While the flints are shown in force fit in the apertures 37, the invention comprehends the use of any suitable flint securing mechanism.

The assembly of the yo-yo herein is simple and substantially foolproof. The yoke 32 is sprung outwardly so that the axis 12 is fitted through aligned bearings 36. The driving cord 24 is then secured to spindle 23 and threaded through hole 35 of the yoke. The cup or shell sections 11 are then fitted on the ends of axis 12 and fixedly secured thereto by screws 13, as shown. The disks 33 of the yoke 32, are sprung outwardly so as to bias the flints 40 in sparking engagement with the abrasive surfacings 30. The sections 11 form a substantially enclosed, hollow chamber, rotatable with and about axis 12. When the yo-yo 10 is rotated on itself, the driving cord 24 is spooled on the spindle 23 as a flat spiral lying in the dead center of the yo-yo. When the yo-yo 10 is thrown out, in any direction, the player holding the free end of cord 24 securely, the casing (11-11), the axis 12, and spool 20 will be projected forwardly with a rotating motion, while the yoke will be restrained by the cord 24, and will not rotate. As a result of this condition, the flints 40 will remain stationary with respect to the yo-yo 10 as it rotates, and the abrasive surfacings 30 will move or rotate with the device and abrade the relatively immovable flints, thereby causing sparking. The sparks liberated will be viewable through the windows 18 and the peripheral slot 16, yet will be wholly contained within the hollow casing of the device because of its improved construction.

When the yo-yo has reached the end of its forward travel, its momentum will cause it to wind itself upon the cord, in the reverse direction, and with continuous sparking, due to the special and uniform biasing of the flints against the oscillating abrasive surfacings, which biasing flows from the special and improved construction and mounting of the yoke within the special bipartite yo-yo casing.

A modification of the yo-yo of Figs. 1-4, and 7, is illustrated in Figs. 5, 6 and 8. Instead of the sheet metal or plastic yoke 32, there is provided a wire yoke 50, desirably of hard drawn brass or of steel. This type of yoke comprises a generally U-shaped member, inverted as shown, and comprised of symmetrical legs 51, joined by an integral cross bar or base 52. The top cross bar or bridge 52 incorporates a central loop 53 defining a driving cord-receiving aperture. The legs 51 incorporate aligned central loops 54, of a diameter sufficient to permit free rotation of axis 12.

At the bottom of legs 51, loops 55 are formed, and serve as flint carriers, as shown. The operation of this form of yo-yo will be identical with that of the type illustrated in Figs. 1-4, and 7. While only one flint is shown on each side of the wire yoke, the invention comprehends the use of any suitable number, depending on the sparking effect desired.

Referring now to Figs. 9, 10 and 13, the modified yo-yo will be seen to comprise the usual casing and driving elements. The abrasive covered surfaces 31 are seen as formed on the outer surface of the disks 21, 22, and are engaged by flints 40 mounted in yoke 50. The yoke 50 comprises a U-shaped member having legs 51, 52, joined by a cross bar 53. The legs 51, 52, are provided with aligned apertures 54, 55, severally corresponding to apertures 36 of yoke member 32. The cord-receiving aperture 56 in section 53 corresponds in position and function to aperture 35 of yoke 32. The legs 51, 52 are formed with aligned flint-receiving apertures 57, 58, and are bowed inwardly, as illustrated in Fig. 9 to bias the flints 40 inwardly against abrasive surfacings 31 on the outside of disks 21, 22. The driving cord 24 is wound on the spindle in the usual manner, and is threaded through hole 56 in yoke 50.

In the form shown in Figs. 11 and 12, the casing sections 11A are flatter than those of the devices of Figs. 1-3, 4-6, and 9-10. The flints 40 are mounted in flint-receiving apertures 62 of the shell casings, and have sparking, bearing engagement against abrasive surfacings 31 formed on the outer surfaces of disks 64, 65, which are joined by bridge section 66, apertured to receive the driving cord in the usual manner. The spacing between the disks 64, 65 corresponds in degree and function to that between the disks 21, 22, which are fixedly secured on the axis 12. The disks 64, 65 are centrally apertured to permit free rotation of axis 12 therein and therethrough. Because of the flattened construction of this type of sparking yo-yo, a lighter, and less bulky device is secured, while retaining the positive and safety sparking features of the other forms of the novel yo-yo herein.

In the use of a looped cord, as illustrated in Fig. 14, the yo-yo rotates in place, about the loop 71 of the cord 70, which is twisted on itself, as indicated at 72. The free end 73 of the twisted cord is secured in any suitable manner, and desirably to a ring 74. With the yo-yo spinning freely about the loop 71 of cord 70, a slight jerk of the cord will cause the loop to bind and the yo-yo will wind up the cord about the spindle section of the axis to permit the operation of the yo-yo in the manner of the forms using a cord fixedly secured to the spindle of the axis.

It will be seen that with the improvements herein, a variety of yo-yo's can be made from standard parts, which are interchangeable in the various forms. Thus the casing is made of identical cup sections, mounted and secured on a standard axis. The axis may incorporate integral spool sections, as in the devices of Figs. 1, 4, and 9. Again the yoke members 32, 50 and 60, are generally similar, and may be severally interchanged by reversing the curvature or bias of the legs, and varying the flint mountings in any desired manner. Likewise, the flattened casing sections 11A of the device of Figs. 11, 12, can be sprung inwardly to insure positive biasing of the flints mounted therein against the cooperating abrasive surfacings.

It will now be appreciated that there has been

provided an improved safety type sparking yo-yo of novel construction, wherein the cooperating sparking and driving elements are wholly encased and protected in and by the body of the yo-yo itself, and the yo-yo is susceptible of sparking action when projected outwardly from the user, and in any direction whatsoever.

What is claimed is:

1. A safety sparking yo-yo comprising a peripherally slotted, hollow, circular casing having a central axis, a grooved hub in the casing and operatively associated with the axis, an operating cord secured on the axis and looped in a flat spiral in the grooved hub and extending through the peripheral slot, said cord adapted to be wound or unwound in either direction during operation of the yo-yo, a spring biasing yoke member in the casing, said yoke member and axis having mating bearing parts for free rotation of the axis and casing about the yoke, said yoke being perforated to receive the operating cord, abrasive surfacings and flints cooperatively associated with the inner walls of the casing, and the yoke, and in mutually spring-biased bearing engagement, the operating cord serving to prevent rotation of the yoke and thereby providing relative movement of the flints and abrasive surfaces to cause sparking of the yo-yo during operation.

2. Yo-yo according to claim 1, comprised of a pair of symmetrical, demountable dished members spacedly mounted on the axis and rotatable therewith, the opposed rims defining the peripheral slot of the casing.

3. Yo-yo according to claim 2, characterized by inturned, rolled rims forming conjoint stiffening sections and spark-receiving pockets, and fenestrations comprised of spaced wall openings.

4. Yo-yo according to claim 3, characterized by internal abrasive surfaces.

5. Yo-yo according to claim 1, characterized by the fact that said grooved hub includes a pair of spaced disks secured about the axis and defining therewith a cord-receiving groove lying in the plane of the peripheral slot, the said groove and slot being substantially equal in width.

6. Yo-yo according to claim 1, characterized by the fact that the yoke members comprise stirrups consisting of a perforated, top saddle section, and depending, spring-biased legs, the legs being provided with a pair of aligned openings adapted to receive the axis therein and form bearing therefor.

7. Yo-yo according to claim 6, characterized by the fact that the legs of the stirrups are also provided with flint holding means.

8. Yo-yo according to claim 7, characterized by the fact that the yokes are formed of spring sheet metal.

9. Yo-yo according to claim 7, characterized by the fact that the yokes are formed of spring wire.

MICHAEL J. DE VINCENT.
